UNITED STATES PATENT OFFICE.

JACKSON H. PRESSLEY, OF OCEANPORT, NEW JERSEY.

RADIO RECEIVING APPARATUS.

Application filed October 16, 1924. Serial No. 743,929.

To all whom it may concern:

Be it known that I, JACKSON H. PRESSLEY, a citizen of the United States, residing at Oceanport, in the State of New Jersey, have invented certain new and useful Improvements in Radio Receiving Apparatus, of which the following is a specification.

This invention relates to a circuit arrangement particularly adapted for the receiving of continuous wave radio telegraph signals. This invention is also adapted for the reception of radio telephone signals by the super-heterodyne method of reception.

15 The primary object is the provision of a circuit arrangement for interlinking a circuit tunable to carrier frequency with a circuit tunable to an oscillating current frequency, so that changes in the tuning of either circuit will in no manner interfere with the tuning of the other circuit.

In order to accomplish this interlinking of the signal frequency circuit and the oscillating circuit using a single oscillator tube, 25 a mesh circuit or Wheatstone bridge is used and the carrier frequency circuit is connected to the tube through one of the conjugate neutral points of the bridge, so that the electrical center of the oscillating circuit is also 30 at the same conjugate neutral point. The plate of the tube is connected through a coil which is inductively coupled to the coils adjacent to this electrical center of the oscillating circuit.

35 Further objects and advantages will be more fully set forth in the attached specification and in the claims. In the drawings

Fig. 1 is a diagrammatic view of one form of my invention.

40 Fig. 2 is a modification thereof utilizing condensers in place of inductances to each side of the main conjugate neutral points, and

45 Fig. 3 is a diagrammatic view of a modification in which two arms of the Wheatstone bridge are formed by the inherent capacity of the tube itself and a separate balancing condenser of equal capacity.

50 Referring to the drawings more particularly by reference numerals and letters, the antenna A is connected to the ground G through the coil t_1 , inductively coupled to the coil t_2 across which is connected the tuning condenser C_t . The tuning circuit is completed by connecting the tuning con-

denser on one side to the conjugate neutral points 2 and 3 of a Wheatstone bridge arrangement B, which is formed by the two parts t_1 and t_2 of a tuning inductance T, the ends of which are connected at the points 4 and 5 respectively, to an oscillator condenser C_o and also to the ends of the impedances Z_1 and Z_2 , the other ends of which are connected together at the neutral point 3, which is electrically connected to the other side 65 of the tuning condenser C_t .

By the arrangement as just described it will be seen that the tuning circuit is connected through the Wheatstone bridge or mesh circuit B to the grid g of an oscillating detector tube O and also to the common point 6 of the filament f and batteries b_1 and b_2 .

As oscillations originating in the antenna circuit are passed through the mesh or bridge circuit, part of the effective voltage 75 resulting therefrom is impressed across the grid circuit of the tube which is connected as shown to the point 4, a suitable grid condenser with shunted resistance leak being connected in series with the grid. Coil 80 5 is inductively coupled to the two coils t_1 and t_2 of the tuning inductance T and this coil r is connected to the plate p of the tube O and to the receiving impedance R, the other terminal of which is connected 85 to the free end of the battery b_2 . The coil r , coils t_1 and t_2 , and the condenser C_o form an oscillating circuit which generates constant oscillations at a frequency determined by the amount of capacity in the 90 condenser C_o which is variable at will. The oscillations generated in the oscillating circuit just mentioned have no effect upon the tuning circuit or upon the antenna circuit, since the tuning circuit is connected across 95 the conjugate neutral points of the mesh circuit B. Similarly, oscillations arising in the tuning circuit have no effect upon the oscillations generated in the oscillating circuit, since the current generated in the tuning 100 circuit divides at the point 2 to flow in opposite directions through the coils t_1 and t_2 , so that their effect due to incoming signals neutralizes each other and have no effect upon the coil r .

In the oscillating circuit and in series with the coil r is a receiving impedance R_1 , inductively coupled to a second impedance in the receiving circuit R_2 . The oscillating circuit permits a self heterodyning action of 110

the tube O so that beat notes, which will have a frequency equal to the difference between the signal frequency and the oscillating current frequency, will be produced so as to be audible in receiving circuit R_2 . The circuit arrangement is adapted to be tuned by the tuning condenser C_2 so as to bring in the station desired. The oscillating circuit is tuned so as to properly heterodyne the incoming waves in the effective arm of the bridge by variations of the oscillating condenser C_0 . Although the oscillations of either the signal frequency circuit or the oscillating current circuit have no effect upon each other due to the manner in which they are connected to the bridge circuit B, they are effectively combined in the one arm of the bridge with which the output circuit is associated, and the incoming signals are heterodyned so as to be audible in the receiving circuit. No radiation can take place from the antenna or from the receiving circuit due to the oscillations of the oscillating circuit, since these oscillations have no effect upon the antenna circuit.

Fig. 2 shows a somewhat similar arrangement of the mesh circuit in which the conjugate neutral points 7 and 8 are adapted to be connected to the carrier frequency circuit. To each side of the neutral point 7 is a condenser 9 and 10 of substantially equal value which replace the coil t_1 and t_2 of Fig. 1. The tuning condenser C_0 of Fig. 1 is substituted by the impedance coil 11 which is inductively coupled to the plate circuit. The effect of the provision of neutral point 1 between the two condensers 9 and 10 is the same as providing it at the electrical center of the coil 11 as regards to any effect of the coil 11 upon the coil 12 corresponding to the coil t Fig. 1.

Fig. 3 shows a second modification which is similar to Fig. 1 as regards the coils t_1 and t_2 of the tuning inductance T and as regards the tuning condenser C_0 of the oscillating circuit. The impedances Z_1 and Z_2 of Fig. 1 are however substituted by the inherent capacity of the oscillator tube represented by q in dotted lines, and by the small condenser C_q having a capacity equal to that of the tube. A condenser C_p of substantially equal value to the plate to grid capacity is connected between the plate and the free end of coil t_2 . The effect of condenser C_p is to enable the bridge to retain its balance over a larger frequency range than otherwise obtainable.

I claim:

1. A circuit system comprising, in combination, an input circuit, an output circuit, a three element vacuum tube having a plate a grid and a filament, a mesh circuit having a conjugate pair of neutral points, said input circuit being connected across said pair of conjugate points, said grid and filament

being connected across nonconjugate points of said mesh, and said plate being electrically coupled to said mesh circuit and to said output circuit.

2. A circuit system comprising, in combination, an input circuit, a three element vacuum tube having a plate a grid and a filament, a mesh circuit having a conjugate pair of neutral points, said input circuit being connected across said pair of conjugate points, said grid and filament being connected across nonconjugate points of said mesh, said plate being inductively coupled to said mesh circuit to produce continuous oscillation in the mesh circuit, and means for varying the frequency of said oscillations.

3. A circuit system comprising, in combination, an input circuit, a three element vacuum tube having a plate a grid and a filament, a mesh circuit having a conjugate pair of neutral points, said input circuit being connected across said pair of conjugate points, said grid and filament being connected across nonconjugate points of said mesh, and said plate being inductively coupled to neutral points of said mesh so as to produce continuous oscillations in the mesh circuit which will not effect said input circuit, and an output circuit connected to said plate.

4. In a self heterodyne receiving circuit, a three element vacuum tube, a mesh circuit, a receiving circuit including a part of said mesh circuit tunable to carrier frequency and connected to the grid of the tube, an oscillating circuit connected to the grid and including part of said mesh circuit and tunable to vary the frequency of the oscillations thereof, the mesh circuit having conjugate neutral points to which the circuits are connected so that a change in the tuning of either of said tunable circuits will not effect the tuning of the other.

5. In a self heterodyne receiving circuit, a mesh circuit including a pair of inductively coupled inductances of substantially equal value, a receiving circuit including part of said mesh circuit connected to the grid of the tube through a conjugate neutral point of the mesh circuit between the two inductances, an oscillating circuit connected to the grid of the tube and including part of said mesh circuit and tunable to vary the frequency of the oscillations thereof, said oscillating circuit including a coil inductively coupled to said two inductances and connected to the plate of the tube, said mesh circuit serving to prevent changes in the tuning of either of said circuits upon change of the tuning of the other.

6. A circuit system comprising, in combination, an input circuit, a three-element vacuum tube having a plate a grid and a filament, a mesh circuit having a conjugate

pair of neutral points, said input circuit being connected across said pair of conjugate points, said grid and filament being connected across non-conjugate points of said mesh circuit, said plate being coupled to said output circuit and to said mesh circuit to produce oscillations in mesh circuit which will not affect said input circuit, means for varying the frequency of said oscillations and means for balancing out the coupling effect of the capacity between said grid and said plate. 10

In testimony whereof I affix my signature.
JACKSON H. PRESSLEY.
